UNITED STATES PATENT OFFICE.

EDWARD T. BAILEY, OF AURORA, ILLINOIS.

HINGE-GAGE.

1,077,785.

Specification of Letters Patent.

Patented Nov. 4, 1913.

Application filed January 15, 1913. Serial No. 742,261.

To all whom it may concern:

Be it known that I, EDWARD T. BAILEY, a citizen of the United States, residing at Aurora, in the county of Kane and State of Illinois, have invented new and useful Improvements in Hinge-Gages, of which the following is a specification.

The invention relates to an improved hinge gage in which the parts are so constructed as to permit the device to be used with hinges of any size and for accurately locating the hinge mortises on the complementary parts, as the door and frame.

The main object of the present invention is the provision of a hinge gage including a rod carrying a series of gaging elements, said elements being constructed to be secured in relative positions at any desired points on the rod and formed to present exact uniform edges to serve as guides for marking after gaging.

The invention in its preferred form of details will be described in the following specification, reference being had particularly to the accompanying drawings, in which:—

Figure 1 is a perspective view illustrating the use of the improved gage. Fig. 2 is a perspective view of the gage removed. Fig. 3 is a perspective view of one of the gaging elements.

Referring particularly to the accompanying drawings, my improved gage includes a rod 1 preferably angular in cross section and of any desired or appropriate length. Secured to one end of the rod is a gage plate 2 the end of which projects beyond the surface of the rod for a purpose which will presently appear. Movable mounted upon the rod are a series of gage elements 3, and as these elements are of identical construction a detailed description of one will suffice for all. Each element includes a sleeve like section 4 slidably fitting the rod and adapted to be held in fixed position on the rod through the medium of a set screw 5 passing through the sleeve. Secured to and projecting from the sleeve at a point thereon diametrically opposite the set screw is a gage arm 6, the opposite surface of which presents an edge 7 at exactly right angles to the rod. The arm is of materially less thickness than the similar dimension of the sleeve and as the arm is arranged centrally of the side of the sleeve from which it projects, the juncture

of the arm and sleeve provide shoulders 8. The gage elements are arranged upon the rod in pairs, being designed to coöperate in pairs and when thus arranged have their marking edges 7 toward each other as will be plain from Fig. 2 of the drawings.

The device may be used in various ways, as for example, in setting each pair of gaging elements at the point at which it is desired that the hinges shall occupy and spacing the elements of each pair a distance apart corresponding to the length of the hinge. The rod is then arranged lengthwise of the door, the gage plate 3 resting upon the upper edge of the door and the side edge of the door resting in one of the shoulders 8 of the gage elements whereby the arms will be arranged transverse the edge of the door. Suitable scribing tool or pencil may be used to mark on the door edge the points at which the respective upper and lower edges of the hinges will terminate, thus indicating the line of cut for the mortise as will be obvious.

Having gaged the door structure the device without change is used for gaging the coöperating door casing, and in this instance the plate 3 being brought against the jamb plate of the frame, and the gaging elements used to indicate the line of cut as in the door structure. The thickness of the gage plate will thus indicate the difference in height of the hinge mortises on the door frame and door thereby providing a clearance for the door equal to the thickness of the plate.

The improvement may be used in any way and for other purposes than gaging hinges as for example, a single gaging element may be set at a desired point and the hinge to be used placed upon the edge 7 of the element and itself form a gage for the upper marking edge. Any number of gaging elements may be used and the device as described is clearly serviceable for determining position for the locks on doors so that all the doors of a building may have locks positioned at uniform height, and it is to be understood that I contemplate any and all purposes to which the device may be put and also the provision of the gaging element in any size or of any material and the provision of a rod of any size and of any material.

What is claimed is:—

A gaging device including a rod, and a plurality of gaging elements secured there-

on, each of said elements including a sleeve 5
slidably mounted upon the rod, a set screw
for securing the sleeve in fixed relation to
the rod, and an arm projecting from the
sleeve and having a marking edge at right
angles to the rod, the relative thickness of
the arm providing shoulders on opposite
sides thereof at the juncture of the arm and
sleeve, and a gage plate carried by one end

of the rod and projecting beyond the sur- 10
face thereof.

In testimony whereof I affix my signature
in presence of two witnesses.

EDWARD T. BAILEY.
